LIGHT FLASHER

Robert A. Redstone, West Covina, Calif., assignor to
Survival & Rescue Inc., Sierra Madre, Calif.

Filed Mar. 29, 1972, Ser. No. 239,412

Term of patent 14 years

Int. Cl. D29—02; D26—02

U.S. Cl. D72—1 E

FIG. 1

FIG. 2

FIG. 3

FIG. 4

FIG. 5

FIG. 1 is a rear elevational view of a light flasher showing my new design;

FIG. 2 is a top plan view thereof;

FIG. 3 is a side elevational view as taken from the left of FIG. 1;

FIG. 4 is a side elevational view thereof as taken from the right of FIG. 1;

FIG. 5 is a bottom plan view thereof.

The front of the light flasher is identical to the rear except for the switch button on the front. The oblique line shading in FIGS. 1, 2, 3 and 4 indicates transparency.

I claim:

The ornamental design for a light flasher, as shown and described.
